(57) **CLAIM**

The ornamental design for a case for electronic device, as shown and described.

DESCRIPTION

FIG. 1 is a front perspective view of a case for electronic device, showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is a rear perspective view thereof;

FIG. 9 is a front perspective view of the case for electronic device of FIG. 1, shown in an alternate position;

FIG. 10 is a front view of FIG. 9;

FIG. 11 is a rear view FIG. 9;

FIG. 12 is a left-side view FIG. 9;

(Continued)

FIG. 13 is a right-side view FIG. 9;
FIG. 14 is a top plan view FIG. 9;
FIG. 15 is a bottom plan view FIG. 9;
FIG. 16 is a rear perspective view FIG. 9;
FIG. 17 is an enlarged view of the encircled portion 17 in
FIG. 1;
FIG. 18 is an enlarged view of the encircled portion 18 in
FIG. 1;
FIG. 19 is an enlarged view of the encircled portion 19 in
FIG. 4;
FIG. 20 is an enlarged view of the encircled portion 20 in
FIG. 4;
FIG. 21 is an enlarged view of the encircled portion 21 in
FIG. 6;

FIG. 22 is an enlarged view of the encircled portion 22 in
FIG. 7;
FIG. 23 is an enlarged view of the encircled portion 23 in
FIG. 9;
FIG. 24 is an enlarged view of the encircled portion 24 in
FIG. 12;
FIG. 25 is an enlarged view of the encircled portion 25 in
FIG. 15; and,
FIG. 26 is an enlarged view of the encircled portion 26 in
FIG. 16.
Dash-Dash broken lines illustrate portions of the case for
electronic device that form no part of the claimed design.
Long dash-short dash broken lines encircling detail view
portions form no part of the claimed design.
